UNITED STATES PATENT OFFICE

WILLIAM GREENBERG, OF PHILADELPHIA, PENNSYLVANIA, ASSIGNOR TO FISCHMAN & SONS, OF PHILADELPHIA, PENNSYLVANIA, A CORPORATION OF PENNSYLVANIA

INSULATING COLLAR FOR ICE CREAM CABINETS

Application filed November 26, 1929. Serial No. 409,922.

This invention relates to improvements in soda fountains or cooling cabinets, and has particular reference to the provision of an improved insulating collar or so-called "breaker strip" which is used in the cooler box or fountain construction at the top of a cooling compartment for the purpose of breaking the metal-to-metal contact between the top capping and the lining of the cooler box.

A further object of this invention is the provision of an improved insulating collar arranged in an efficient and protected relation in a soda fountain or cooler box construction over a compartment which is adapted to receive a plurality of ice-cream cans or other containers, through which a dispenser may reach for quick and convenient access to either of the cans without liability of personal injury, or injury to the collar or other parts of the fountain structure.

A further object of this invention is the provision of an improved capping structure for soda fountains, cooler boxes and the like, provided with an opening therethrough above the ice-cream or other compartment, which flares downwardly into the compartment with an increasing dimension, particularly in the direction of the front of the fountain, in order that convenient access may be had to the foremost of a plurality of cans or other receptacles below the opening.

A further object of this invention is the provision of an improved insulation collar for the openings in cappings of soda fountains and the like, which is preferably cast in one piece and defines an oval opening; the end of which facing the front of the fountain is flared downwardly to increase the size of the opening.

A further object of this invention is the provision of improved means for protecting the lower edges of insulation fountain capping collars from being damaged as an incident of contact with dippers and the like.

Other objects and advantages of this invention will be apparent during the course of the following detailed description.

In the accompanying drawings, forming a part of this specification, and wherein similar

reference characters designate corresponding parts throughout the several views,

Figure 1 is a vertical sectional view taken transversely through an ice-cream can chamber or compartment of a soda fountain.

Figure 2 is a perspective view of an insulation collar of the improved type.

Figure 3 is a fragmentary plan view showing the relation of the opening in the cap of the soda fountain with respect to syrup pumps and adjacent fountain details, and with respect to cans received in the cooler compartment.

Figure 4 is a plan view of the improved insulation collar.

Figure 5 is a side elevation of the improved insulation collar.

Figure 6 is a fragmentary view, partly in section, showing the improved insulation collar in place in the capping and with supporting details of the closure; the view being taken substantially on the line 6-6 of Figure 3.

It is highly desirable to manufacture soda fountains which are relatively narrow, and yet which will contain all of the essential details and units. The length of a fountain may of course be arranged to suit, and the height of soda fountains are substantially fixed. However, the width, that is from front to rear, should be as small in dimension as possible, because of the saving in material and economy in manufacture; to facilitate and expedite production because of the ease of handling during manufacture; to enable compact storage, and ease of installation through narrow doorways and the like, and most important, to expedite service because all units of the narrow fountain are within easy reach of the dispenser. With wide soda fountains the dispenser must necessarily lean over and reach farther for syrups, soda water, etc. and this not only tires the dispenser, but slows up service considerably. With the narrowness of the fountain as a dominant characteristic, and bearing in mind that soda fountains must receive quite a number of ice-cream cans and containers, the present construction requires that the syrup rack

slightly overhang the ice-cream can com-

partments or chambers, so that in the case of the two-can chamber or compartment it is sometimes difficult to arrange the openings in fountains so that the contents of the foremost can may be reached with ease. However, with the improved collar of this invention the difficulties are obviated to great extent.

The fountain as shown may generally be designated by the letter A, and it includes a base 10 supported as by legs 11, and it is provided with upstanding walls 12 at the front, rear, and ends thereof, of any approved material. A counter 14 is provided at the top 10 of the front wall structure of the fountain, and just rearwardly below the counter 14 is disposed the supporting structure 15 of the capping B for receiving the jars 17 adapted to receive syrups and fruits. The cabinet 15 structure of the fountain receives therein brine tanks 20, and suitable metal liners 21, the side walls of which are spaced therefrom for receiving the circulating brine. The tank 20 and its liner 21 of course terminate immediately below the capping B, as is the case in conventional practice, and the liner 21 defines therein a compartment 25 which in cross section is elongated from front to rear of the fountain and adapted to receive front and rear cans or containers 27 and 28 respectively. The cans or containers may receive ice-cream, as is usual, or may receive any other substances desired.

The capping B includes the metal top wall 30 which extends about and forms part of the jar rack or support 15 and which extends to the rear wall 12 of the fountain where it is detachably connected. It includes the insulation cork or other filler 31 and the insulation lining 32, preferably of hard rubber, synthetic resin, or the like. Openings are provided therethrough lined with the improved insulation collars C.

The insulation collar C may be made of a synthetic resin, although preferably, for purposes of economy, it is constructed of hard rubber. It extends from the top of the metal receptacle liner 20 through the thickness of the capping B to the top thereof, and serves to break the metal-to-metal contact between the metal liner and the metal top wall of the capping, all of which prevents condensation of moisture externally upon the capping or the closures over the opening through the collar, as has been well understood in this art for many years. It is to be particularly noted that the opening 40 which receives the collar C lies substantially flush with the vertical rear of the metal liner 20, and extends therefrom forwardly, terminating short of the front of the metal liner 20, as shown in Figure 1, and overhangs only a rear portion of the front ice-cream can 27, when positioned in the chamber 25.

The collar C is of band-like material of

any approved height, and the material thereof is relatively thin. It includes the side wall portions 45 and 46, substantially parallel, and the arcuated rear end wall 47. The portions 45, 46, and 47 are all of the same height. The opposite end wall of the collar is provided with an upper arcuated relatively short portion 49 and therefrom the remaining portion 50 of this end of the collar C flares divergently downwardly with a sort of visor effect, for the purpose of increasing the size of the opening through the collar C at the forward end. That is, the length of the opening 51 through the collar C is less at the top of the collar where it opens on the top of the capping B, than at the bottom of the collar where it opens into the chamber 25; the increase in size being all at the front end of the collar C for the purpose of enabling an easy access to the can 27, as will be perfectly apparent. The upper marginal portion 49, and the other upper margins entirely about the collar C are received in beading 55 formed in the metal top wall 30 of the capping B for the purpose of providing an effective joint and anchoring the collar C in place. The collar C is of less vertical height at the forward end, that is, the lower edge at 55^a terminates flush with the lower surface 32 of the capping, whereas the lower edge 56 along the sides and rear of the collar C terminates at a lower level into the chamber 25, as can readily be seen from Figure 1 of the drawings. The edges 55^a and 56 are convexly arcuated, as shown clearly at 70^a in Figure 6 of the drawings, so that no sharp edges or corners are presented to the compartment 25. This prevents to a great extent the chipping of the shoulder as an incident of contact with metal parts, such as dippers, and prevents injury to an operator's arm or hand should it contact therewith.

As a further expedient in preventing damage to the rear and sides of the collar, especially surrounding the rear can 28, the metal liner 21 is convexly beaded at 70, bulging into the compartment 25 at the top thereof immediately below the lower edge of the rear end and adjacent sides of the collar C, as a protection for the lower edge of the collar at these locations. This beading not only prevents injury to the collar by warding off dippers, but it prevents the cans, as they are lowered or removed with respect to the chamber 25, coming directly in contact with the lower portion of the collar.

Any approved type of closure means may of course be provided for shutting off the opening through the collar. In the present instance I provide a pair of hingedly connected insulated closure lids 75 and 76, hingedly connected at 77 on a line at right angles to the major axis of the opening through the collar C, at a location midway between the ends of the opening through the capping.

These lids 75 and 76 are provided with handles or knobs 79 for the respective swinging thereof as a means of securing access to the cans 27 and 28, as will be readily understood by those skilled in this art.

5 The means of mounting the closure lids is preferably disposed at the axis or pivot axle 77, and preferably comprises a detachable supporting rail or gutter 80, supported at the ends thereof by means of suitable supporting brackets 81 which are secured in the capping beneath the metal wall 30 thereof, and extend into the area at opposite sides of the opening 40; the collar C in the opposite walls 45 and 46 thereof being downwardly notched, as shown at 85 in Figure 2 of the drawings to accommodate these brackets.

From the foregoing description of this invention it is to be seen that an improved substantially oval-shaped insulation capping 20 collar for soda fountains has been provided, which is particularly well adapted to insure an easy access to both containers of the two can ice-cream containers of a soda fountain, together with a conservation in space and bulk of the fountain. While these collars may be formed in strips and subsequently shaped, they are preferably cast integral, eliminating any appearance of seams. The 25 inside surface is polished and of course the bottom edges are rounded and smooth as mentioned.

30 Various changes in the shape, size, and arrangement of parts may be made to the form of invention herein shown and described, without departing from the spirit of the invention or the scope of the claims.

I claim:

1. As an article of manufacture an elongated insulation collar for use in defining an 40 access opening to the compartment of a soda fountain or cooler cabinet, of band-like insulation material having an elongated opening therethrough, the collar being flared divergently downwardly to increase the size of 45 the opening from the top of the collar towards the bottom thereof.

2. As an article of manufacture an insulation protecting collar for use in the access 50 openings of refrigerated containers formed of rigid insulation material being relatively shallow in thickness and having considerable depth, said collar being elongated to define an elongated opening therethrough, the collar 55 at one end being flared downwardly divergent with respect to the other end to increase the size of the opening from the top edge of the collar downwardly.

3. In a soda fountain capping the combination of a metal top having relatively thick 60 insulation material secured therewith and having an elongated transverse opening therein, and an elongated insulation collar in the opening having an elongated opening therethrough, said opening increasing in size

from the top of the capping in the direction of the bottom thereof.

4. In soda fountain structures the combination of a cabinet-like body having a metal tank therein defining an upwardly opening compartment, a removable capping having an opening as access to said tank, an insulation collar surrounding the opening in the capping, the collar being relatively high and shallow in thickness, closure means for the opening to the collar of the capping, and means formed on the top of said tank and overlapping beneath the lower margin of said collar for protecting the same against injury by reason of insertion or extraction of articles through the collar with respect to said tank.

5. In a soda fountain the combination of a cabinet including a compartment having insulated surrounding bottom, side, end, and top walls, the top wall having an opening therethrough of less horizontal cross area than the horizontal cross area of the adjacent part of the compartment, and an insulation collar mounted in said top wall surrounding said opening throughout its depth and having an opening flaring from the top edge of the collar in a divergent relation to substantially the bottom edge of the collar increasing the size of the opening from the top of the top wall toward the bottom of the top wall.
